UNITED STATES PATENT OFFICE

170,671

RADIO CABINET

Lawrence H. Wilson, Grosse Pointe, Mich., assignor to Admiral Corporation, Chicago, Ill., a corporation of Delaware

Application June 22, 1953, Serial No. 25,607

Term of patent 14 years

(Cl. D56—4)

To all whom it may concern:

Be it known that I, Lawrence H. Wilson, a citizen of the United States, residing at Grosse Pointe, in the county of Wayne, State of Michigan, have invented a new, original, and ornamental Design for a Radio Cabinet, of which the following is a specification, reference being had to the accompanying drawings, forming a part hereof.

Fig. 1 is a front elevational view of a radio cabinet, showing my new design;

Fig. 2 is a fragmentary sectional view thereof taken on line 2—2 of Fig. 1; and

Fig. 3 is an elevational view of the right side of the cabinet, broken away to a plane indicated by line 3—3 of Fig. 1.

The left side of the cabinet resembles the right side and the back is plain.

The dominant features of my design reside in the portions indicated by full lines of the drawing.

I claim:

The ornamental design for a radio cabinet, as shown and described.

LAWRENCE H. WILSON.
